OVERCAP FOR AN AEROSOL PACKAGE
OR THE LIKEGeorge B. Fahlstrom, Williamsville, N.Y., assignor to Animal Repellents, Inc., Buffalo, N.Y.

Filed Mar. 6, 1964, Ser. No. 78,898

Term of patent 14 years

(Cl. D58—26)

Fig. 1.

Fig. 2.

Fig. 3.

Fig. 4.

Fig. 5.

FIG. 1 is a front elevational view of an overcap for an aerosol package or the like, showing my new design therefor;

FIG. 2 is a side elevational view thereof;

FIG. 3 is a rear elevational view thereof;

FIG. 4 is a top plan view thereof; and

FIG. 5 is a bottom plan view thereof.

The side not shown is identical to that shown in FIG. 2.

The portions shown in broken lines are for illustrative purposes only.

I claim:

The ornamental design for an overcap for an aerosol package or the like, substantially as shown and described.
